UNITED STATES PATENT OFFICE.

WILLIAM A. GILE, OF CLIFTONDALE, MASSACHUSETTS, ASSIGNOR, BY MESNE ASSIGNMENTS, TO GEORGE K. WOODWORTH, OF BROOKLINE, MASSACHUSETTS.

INTERNAL-COMBUSTION ENGINE.

Application filed May 9, 1916. Serial No. 96,421.

To all whom it may concern:

Be it known that I, WILLIAM A. GILE, a citizen of the United States, and a resident of Cliftondale, in the county of Essex and 5 State of Massachusetts, have invented a new and useful Improvement in Internal-Combustion Engines, of which the following is a specification.

My invention relates to internal combustion engines and more especially to engines of the combined pump and motor cylinder type, either single or double acting, and its object is to provide a simple and efficient means actuated by the main crank for controlling the motion of the sub-piston.

The drawings which accompany and form a part of this specification show an illustrative embodiment of my invention, but it is to be understood that the construction herein 20 particularly described may be widely varied without departing from the scope of my invention as defined by the appended claims.

In the drawings—

Figure 1 is a central longitudinal section 25 of a single-acting engine embodying my improved sub-piston control. Fig. 2 is a central longitudinal section taken on the line 2—2 of Fig. 1. Figs. 3, 4, 5 and 6 are diagrams showing the positions of the moving 30 parts at various points in the cycle.

In the particular drawings selected for more fully disclosing my invention, 1 represents a frame, herein shown as a two-part casing having its parts connected by the 35 bolts 2 and enclosing the lower portion of the engine. Secured to the top of the casing by the bolts 3 is a cylinder 4, the lower end of which is open and projects into said casing and the upper end of which is closed 40 by the head 5 attached by the bolts 6 and is provided with a number of fuel passages or flutes 7 arranged lengthwise in its bore and communicating with the combustion chamber A. Any suitable number of flutes, say 45 from 16 to 20, more or less, may be used. A spark-plug 8 is screwed into the cylinder head, its points projecting into the combustion chamber, and the cylinder and head are water-jacketed as shown at 9, 10.

Arranged to reciprocate within the cylinder 50 is a power piston 11, herein shown as a trunk

piston or plunger, and a double pitman 12 engages the pin 13 secured in the walls thereof and connects said piston to the wrist pin 14 of the crank 15 to transmit the power developed in the cylinder to the main crank shaft 16 journaled in the bearings 17 integral with the engine frame. A relatively-light, imperforate or valveless sub-piston 18 is arranged to reciprocate within the cylinder between the power piston and the combustion chamber, and its rod 19 passes through and is guided by a longitudinal bore in the central core of the power piston, its lower end being pivotally connected to the double link 20 which in turn engages the arm 21 of the rock shaft 22 journaled in the sides of the frame and passing across the latter above the main shaft and to the rear thereof. A rod 23 connects the shorter arm 24 on said rock shaft with the arm 25 integral with the rock shaft 26 which is journaled between the frame and a block 27 rising from the base of said frame. The hub 28 of the connecting rod 29 is in engagement with the wrist pin of the crank, being arranged between one arm of said crank and the box of the pitman 12, and is pivotally connected with the longer arm 30 of the rock shaft 26.

The cylinder has an exhaust passage 27 controlled by the inwardly-opening valve 28 normally held to its seat by the spring 29 which surrounds the valve-stem 30' and bears against the valve housing and the collar 31 on said stem. The valve may be opened by any suitable mechanism, such, for example, as the tappet 32 actuated by the cam 33 which co-operates with the head 34 thereof, gearing (not shown) being employed to connect the cam-shaft 35 with the crank-shaft.

The fuel inlet 36 is located a short distance above the lower end of the power piston when the latter is in explosion position at the end of its up-stroke, as shown in Fig. 2, and may be connected to any suitable source of fuel.

It will be understood of course that the foregoing detailed description comprises various elements which in the precise form shown in the drawings and described herein are not essential to my invention and that

these parts may be considered simply as typical of the necessary elements of an internal combustion engine.

By means of the flutes or fuel passages 5 7 I secure an intimate and substantially perfect mixture of the fuel charge and this results in practically complete combustion. As the power piston approaches the head 10 of the sub-piston the charge which is contained in the space between these two elements is compressed and forced by such compression around the advancing head of the sub-piston through the restricted passage afforded by the flutes or fuel passages and is 15 shot with great force against the cylinder head in a number of relatively small streams.

An explosion of the compressed charge in 20 the combustion chamber acts directly on the head of the sub-piston and by the latter is communicated to the power piston. It is absolutely necessary that the two pistons shall travel at the same rate of speed without the slightest relative movement until the 25 sub-piston shall have covered the inner ends of the flutes. The reason for this will be obvious from an inspection of Fig. 1 in which the parts are shown in the position occupied immediately prior to ignition in the combustion chamber A. Should the 30 power piston begin to move away from the sub-piston before the latter covers the inner ends of the flutes, a portion of the effect of the explosion will be exerted against the lower face of said sub-piston in opposition 35 to the force exerted on the upper face thereof. It is essential also that the subsequent relative movement between the pistons be created positively.

The positive relative movement of the 40 sub-piston with respect to the power piston is created by the main crank which communicates the necessary motion to the sub-piston through the connecting rod 29, the two rock-shafts 26, 22 and their arms, the 45 rod 23 and the link 20. The operation of these elements will be explained with reference to Figs. 3, 4, 5 and 6, on which the several moving parts are indicated by lines identified by reference numerals corresponding 50 to those used on Figs. 1 and 2 and provided with exponents I, II, III, etc., to designate the successive positions of said parts.

When both pistons are at the upper ends 55 of their strokes (explosion position) as shown in Figs. 1, 2 and 3, and the charge compressed in the combustion chamber, the valve 28 being closed, the charge is fired and the resulting explosion causes both pistons to descend at the same initial rate of speed and without any relative movement until the crank which rotates in the direction of the arrows, has passed from its initial position 15 (Fig. 3) to a point a little 60 less than 135 degrees therefrom. The sub-

piston having reached substantially the end of its down-stroke, now begins to lag and the power piston, continuing its descent, moves away therefrom until the crank has passed about 135 degrees from 70 its initial position to 15' (Fig. 4) the crank now being in line with the connecting rod 29 which now has the position 29'. The sub-piston has now reached the lower end of its stroke at 18' with its lower face just 75 above the fuel inlet and the upper face of the power piston is just below said inlet.

The power piston continues its descent until it reaches position 11", the end of its down-stroke (Fig. 5) the crank now being 80 at 15", but immediately after the crank arrived at 15' and while the power piston was descending from 11' to 11", the sub-piston began to ascend, the rock-shaft 26 being rotated counter-clockwise by the 85 movement of the crank beyond 135 degrees and thereby forcing the rod 23 upwardly, so that in the position of the parts represented in Fig. 5 the power piston is momentarily stationary and the sub-piston moving 90 upwardly. The relative movement between the pistons creates a vacuum or a partial vacuum in the space between the same and a charge of fuel is drawn into said space, and, as will be evident, the pumping action 95 which sucks in the charge is caused mainly by the rapid upward movement of the sub-piston, for the power piston travels but a short distance from the position it occupies at the end of the down-stroke of the 100 sub-piston to its position 11", which is the end of its own down-stroke. The exhaust valve 28 opens practically simultaneously with or preferably shortly before the commencement of the up-stroke of the sub-pis. 105 ton and the burnt gases of the preceding explosion are mechanically expelled by the latter. The crank continuing its clockwise rotation the power piston ascends, and, when the former reaches a point 15" 110 (Fig. 6) about 240 degrees from initial position, the sub-piston has arrived at explosion position, the arms 25, 30, 24, 21, then being in their respective initial positions. From this point until the crank reaches its 115 initial position the sub-piston remains substantially stationary, its lower face taking successively the positions 18^{iv}, 18^v, 18^{vi}, 18^{vii} indicated in dotted lines on Fig. 6, and the crank 15 and rocker arms 25, 24, 21 120 taking the dotted line positions correspondingly marked. In other words, the sub-piston having arrived at the end of its up-stroke or at explosion position 18^{vii} when the crank arrived at 15^{vii}, settles back a 125 fraction of an inch and then rises again to explosion position while the crank is moving from 15^{vii} to 15, its initial position.

A few degrees rotation of the crank beyond the position 15^{vii} will cause the power piston 130

to cover the fuel inlet whereupon it begins to compress the charge in the space between its upper face and the lower face of the sub-piston. A portion of the gas so compressed 5 passes around the head of the sub-piston through the flutes to the combustion chamber and pneumatically expels the remaining portion of the burnt gas through the exhaust passage whereupon the exhaust valve closes. 10 The power piston then continues its upward stroke further compressing the charge and driving the same with great force through the flutes into the combustion chamber thereby shooting the charge against the cylinder. 15 head in a plurality of relatively small streams and effecting the thorough mixture of the same, until the crank having arrived at 15, its up-stroke is completed, whereupon ignition occurs and the cycle is repeated, 20 there being one explosion at the end of every up-stroke or one per revolution of the crank-shaft.

It will be obvious that by duplicating the sub-piston control apparatus, my invention 25 may be applied to a double-acting engine having two sub-pistons, one on each side of the power piston.

While I have described in detail the relative movement of the parts which I have 30 found to be satisfactory in practice, it will be understood that I do not limit myself specifically thereto, for said parts may be variously adjusted and timed and other cycles may be effected.

35 I claim:

1. An internal combustion engine comprising a cylinder, a power piston and an imperforate sub-piston, both arranged to reciprocate within said cylinder, said sub-piston 40 being located between the combustion chamber and said power piston, a main shaft provided with a crank, means for controlling said sub-piston positively throughout the entire cycle, a member connecting said 45 means directly to said crank, and means pivotally connecting said power piston to said crank.

2. An internal combustion engine comprising a cylinder, a power piston and an imperforate sub-piston both arranged to reciprocate within said cylinder, said sub-piston 50 being located between the combustion chamber and said power piston, a main shaft provided with a crank, means actuated directly by said crank for controlling said sub-piston positively throughout the entire 55 cycle, and a pitman connecting said power piston to said crank.

3. An internal combustion engine comprising a cylinder provided with a combustion chamber at one end only, an imperforate sub-piston and a power piston both arranged to reciprocate within said cylinder, said sub-piston having a single head 65 located between said combustion chamber

and said power piston, a main shaft having a crank, means actuated directly by said crank for controlling said sub-piston, and a pitman connecting said power piston to said crank. 70

4. An internal combustion engine comprising a cylinder, a power piston and an imperforate sub-piston both arranged to reciprocate within said cylinder, a main shaft having a crank and means actuated directly 75 by said crank for causing positive movement of said pistons at the same initial rate of speed for a substantial portion of the power stroke and for causing, subsequently, positive relative movement between the 80 same.

5. An internal combustion engine comprising a cylinder, a power piston and an imperforate sub-piston both arranged to reciprocate within said cylinder, a main shaft 85 having a crank and means actuated directly by said crank for causing positive movement of said pistons initially at the same rate of speed without relative movement for a substantial portion of the power stroke and 90 subsequently at different rates of speed.

6. An internal combustion engine comprising a cylinder, a power piston and a sub-piston both arranged to reciprocate within said cylinder, a main shaft having a crank, a 95 rock-shaft journaled in proximity thereto, two arms on said rock-shaft, a connecting rod pivotally engaging said crank and one of said arms, a second rock-shaft journaled in proximity to said main shaft, two arms on 100 the last mentioned rock-shaft, a rod connecting the second arm of the first mentioned rock-shaft to one of the arms of the second rock-shaft and a link connecting the other arm of the second rock-shaft to the rod of 105 said sub-piston.

7. An internal combustion engine comprising a cylinder, a power piston and a sub-piston both arranged to reciprocate within said cylinder, a main shaft having a 110 crank, a rock-shaft journaled below said main shaft, two arms on said rock-shaft, a connecting rod pivotally engaging said crank and one of said arms, a second rock-shaft journaled above said main shaft, two arms 115 on the last mentioned rock-shaft, a rod connecting the second arm of the first mentioned rock-shaft to one of the arms of the second rock-shaft and a link connecting the other arm of the second rock-shaft to the rod of 120 the said sub-piston.

8. An internal combustion engine comprising a cylinder, a power piston and a sub-piston both arranged to reciprocate within said cylinder, a main shaft having a 125 crank, a rock-shaft journaled below said main shaft, two arms of unequal length on said rock-shaft, a connecting rod pivotally engaging said crank and the longer arm of said rock-shaft, a second rock-shaft jour- 130

- naled above said main shaft, two arms of unequal length on the last mentioned rock-shaft, a rod connecting the shorter arm of the first mentioned rock-shaft to the shorter arm of the second rock-shaft and a link pivotally connecting the longer arm of the second rock-shaft to the rod of said sub-piston.
9. An internal combustion engine comprising a cylinder, a power piston and an imperforate sub-piston both arranged to reciprocate within said cylinder, a main shaft having a crank, and means actuated directly by said crank for causing said pistons to travel at the same rate of speed until the sub-piston reaches substantially the end of its power stroke and for causing, subsequently, positive relative movement between the same.
10. An internal combustion engine comprising a cylinder, a power piston and an imperforate sub-piston both arranged to reciprocate within said cylinder, a main shaft having a crank, means actuated directly by said crank for causing said pistons to travel at the same rate of speed until the sub-piston reaches substantially the end of its down-stroke, for causing, subsequently, positive relative movement between the same and for holding the sub-piston substantially stationary at the end of its up-stroke until the power piston completes its up-stroke.
11. An internal combustion engine comprising a cylinder provided with a combustion chamber at one end only, an imperforate sub-piston and a power piston both arranged to reciprocate within said cylinder, said sub-piston having a single head located between said combustion chamber and said power piston, a main shaft having a crank, means for causing the sub-piston to travel in contact with the power piston during a substantial portion of the power stroke and for causing, subsequently, positive relative movement between said pistons, and a member connecting said means directly to said crank.
12. An internal combustion engine comprising a cylinder, a power piston and a sub-piston both arranged to reciprocate within said cylinder, a main shaft having a crank, means actuated directly by said crank for causing positive movement of said pistons at the same initial rate of speed without relative movement for a substantial portion of the power stroke and for causing, subsequently, positive relative movement between the same, and means whereby the charge of fuel in said cylinder is transferred under pressure from the space between said pistons through a restricted passage to the combustion chamber.
13. An internal combustion engine comprising a cylinder, a power piston and a sub-piston both arranged to reciprocate within said cylinder, a main shaft having a crank, means actuated directly by said crank for causing positive movement of said pistons at the same initial rate of speed without relative movement for a substantial portion of the power stroke and for causing, subsequently, positive relative movement between the same, and means whereby the charge of fuel in said cylinder is mixed during compression.
14. An internal combustion engine comprising a cylinder, a power piston and a sub-piston both arranged to reciprocate within said cylinder, a main shaft having a crank, means actuated directly by said crank for causing positive movement of said pistons at the same initial rate of speed without relative movement for a substantial portion of the power stroke and for causing, subsequently, positive relative movement between the same, and means whereby the charge of fuel in said cylinder is transferred under pressure from the space between said pistons to the combustion chamber in a plurality of relatively small streams.
15. An internal combustion engine comprising a cylinder having a plurality of fuel passages arranged lengthwise in its bore at one end thereof, a power piston and a sub-piston both arranged to reciprocate within said cylinder, a main shaft having a crank and means actuated directly by said crank for causing positive movement of said pistons at the same initial rate of speed without relative movement for a substantial portion of the power stroke and for causing, subsequently, positive relative movement between the same.
16. An internal combustion engine comprising a cylinder having a plurality of fuel passages arranged in its bore near one end thereof, said fuel passages communicating with the combustion chamber of the engine, a power piston and a sub-piston both arranged to reciprocate within said cylinder, a main shaft having a crank and means actuated directly by said crank for causing positive movement of said pistons at the same initial rate of speed without relative movement for a substantial portion of the power stroke and for causing, subsequently, positive relative movement between the same.
17. An internal combustion engine comprising a cylinder provided with a combustion chamber, an imperforate sub-piston and a power piston both arranged to reciprocate within said cylinder, said sub-piston being located between said combustion chamber and said power piston, a main shaft having a crank, means for causing the sub-piston to travel in contact with the power piston during a substantial portion of the power stroke and for causing, subsequently, positive relative movement between the same, and means whereby the charge of fuel in said cylinder is transferred under pressure from the space between said pistons to the combustion chamber.

18. An internal combustion engine comprising a cylinder, an imperforate sub-piston and a power piston both arranged to reciprocate within said cylinder, a main shaft having a crank, means for causing the sub-piston to travel in contact with the power piston during a substantial portion of the power stroke and for causing, subsequently, positive relative movement between said pistons, and a member connecting said means directly to said crank. 55
19. In a two cycle internal combustion engine, a cylinder having an inlet port near one limit of the plunger movement and an exit port near the opposite limit of the plunger movement, a main plunger connected to a crank shaft and having a reciprocating movement in said cylinder to open and close said inlet port, a valveless supplemental reciprocating plunger movable away from said main plunger when said inlet port is uncovered by the main plunger to eject the spent gas and to introduce fresh combustible gas in advance of the main plunger at each cycle of movement thereof, and ports in the cylinder wall at one end thereof to enable the fresh charge to pass said supplemental plunger. 60
20. In a two cycle internal combustion engine, a cylinder having inlet and exit ports located near opposite limits of the plunger movement, a main reciprocating plunger, a valveless supplemental reciprocating plunger movable independently of said main plunger through a portion of the cycle of movement of said main plunger to eject the spent gases from the cylinder and introduce a fresh charge of combustible gas into the cylinder in advance of the forward movement of the main plunger, and means at one end of the cylinder to pass the fresh charge around said supplemental plunger. 65
21. In a two cycle internal combustion engine, a cylinder having an inlet port near one limit of the plunger movement and an exit port and by-pass ports near the opposite limit of the plunger movement, a main reciprocating plunger, and a light weight valveless supplemental reciprocating plunger movable independently of said main plunger through a portion of the cycle of movement of said main plunger to eject the spent gases from the cylinder and in- 70
